(57) **CLAIM**

The ornamental design for a drilling tool tip, as shown and described.

DESCRIPTION

FIG. 1 is a front view of a drilling tool tip;
FIG. 2 is a right hand side view of the drilling tool tip of FIG. 1 turned 90° about its axis,
FIG. 3 is a left hand side view of the drilling tool tip,
FIG. 4 is a rear view of the drilling tool tip,
FIG. 5 is a bottom view of the drilling tool tip; and,
FIG. 6 is a top view of the drilling tool tip.
FIG. 7 is a bottom, perspective view of the drilling tool tip; and,
FIG. 8 is a top, perspective view of the drilling tool tip.
Broken lines shown in the drawings are for illustrative purposes only and form no part of the claimed design.
